UNITED STATES PATENT OFFICE.

JOHN W. HASBURG, OF CHICAGO, ILLINOIS.

DESIGN FOR A COMBINED PAINT PRODUCT AND PALETTE.

45,421.

Specification for Design.

Patented Mar. 17, 1914.

Application filed November 13, 1911. Serial No. 660,149. Term of patent 14 years.

To all whom it may concern:

Be it known that I, JOHN W. HASBURG, a citizen of the United States, residing at Chicago, in the county of Cook and State of Illinois, have invented a new, original, and ornamental Design for a Combined Paint Product and Palette, of which the following is a specification, reference being had to the accompanying drawing, wherein I have shown my new design.

I claim:

The ornamental design for a combined paint product and palette, as shown.

JOHN W. HASBURG.

Witnesses:

MARY G. ALLEN,
W. LINN ALLEN.
